UNITED STATES PATENT OFFICE.

JOHN L. LEWIS, OF PITTSBURG, PENNSYLVANIA, ASSIGNOR TO THE LEWIS FOUNDRY AND MACHINE COMPANY, (LIMITED,) OF SAME PLACE.

SHEET-METAL-CORRUGATING ROLL.

SPECIFICATION forming part of Letters Patent No. 329,322, dated October 27, 1885.

Application filed August 4, 1885. Serial No. 173,540. (No model.)

To all whom it may concern:

Be it known that I, JOHN L. LEWIS, of Pittsburg, in the county of Allegheny and State of Pennsylvania, have invented certain new and useful Improvements in Sheet-Metal-Corrugating Rolls; and I do hereby declare that the following is a full, clear, and exact description of the invention, which will enable others skilled in the art to which it applies to make and use the same, reference being had to the accompanying drawings, which form a part of this specification.

Machines for corrugating sheet metal are composed, essentially, of two longitudinally fluted or grooved rolls, the grooves being alike in both and symmetrical, the rolls being journaled in ordinary housings, and each roll driven by positive gearing. The common mode of gearing is to fit the roll-neck 10 (outside the housing) with a worm-gear and drive it by means of a worm on a vertical shaft; but whether the gearing be of the worm form or ordinary spur-gearing be used, the following difficulty arises in use: When it becomes necessary to raise the upper roll to accommodate thicker sheet metal, the act of raising the bearings and roll partially rotates the roll itself, since its gear-wheel is engaged with the worm, which acts as a stop and pivot point. The result is that the partial rotation thus necessarily given the upper roll entirely disarranges the symmetrical relation between the ridges on one roll and the grooves on the other; but for the proper operation of 20 corrugating-rolls these ridges and grooves must be always maintained in one definite relation—namely, with an equal space at all points and positions. The slightest disturbance of this relation causes the ridge on one roll to approach the adjoining ridge on the other roll, thereby tending to grind the metal passing between them. My object is to prevent this result; and therefore my present invention consists in the novel construction and 30 arrangement of the rolls and gearing, whereby the tendency of the upper roll to revolve forwardly or backwardly by the raising of the same will be offset by a corresponding change in the relation of the driving-gear.

Referring to the accompanying drawings, illustrating my improvement, Figure 1 is an

end elevation of the rolls with gearing required, and Fig. 2 a sectional view of worm and worm-shaft; Fig. 3, an elevation of the rolls and gearing; Fig. 4, a sectional view of a detail.

A is the lower or fixed corrugating-roll, and B is the upper or adjustable corrugating-roll. Both are adapted to be positively driven by means of the worm-gear.

The drawings show the gearing for driving the upper roll, B, on the right-hand side of Fig. 1, that for driving the lower roll being at the opposite end, as shown in Fig. 3, and both receiving motion from the horizontal 45 shaft C and suitable miter or beveled gears. The worm-wheel D, keyed on the neck of roll B, meshes with the worm E, which is bored out to fit on vertical shaft f, the latter having a spline, g, and the worm E having the longitudinal groove h in its inner face. Thus the worm E can be moved up and down the shaft f, but cannot turn thereon. Shaft f is threaded for a suitable distance at each end of the normal position of worm E, and fitted 50 with the nuts i and the jam-nuts i'. The shaft f is suitably journaled and geared to the driving-power. Now, when an upward adjustment of roll B becomes necessary to accommodate thicker sheet metal, by loosening the nuts i i' the worm E may be raised in exact coincidence with the roll B, or vice versa when roll B is to be lowered, after which the nuts i i' are tightened again, and the roll B will not have lost its symmetrical relation 55 with the roll A. Obviously, the two rolls A and B can be driven by a single vertical shaft at one end having two worms, one right-handed and the other left-handed, and the upper worm arranged as I have described.

What I claim, and desire to secure by Letters Patent, is—

1. In a corrugating-machine composed of two corrugating-rolls, one of which is adjustable to or from the other, and both positively driven, the combination, with the adjustable roll, of driving-gear adapted to be correspondingly adjusted in the same direction, substantially as described, whereby the symmetrical relations of the two rolls are preserved.

2. In a corrugating-machine composed of

the roll A and the adjustable roll B, the combination, with said roll B, of the worm-wheel D, the grooved worm E, vertical driving-shaft f, having spline g, and threaded as described.

5 scribed, nuts i, and jam-nuts i', substantially as described.

In testimony that I claim the foregoing as

my own I have hereto affixed my signature in presence of two witnesses.

JOHN L. LEWIS.
